UNITED STATES PATENT OFFICE.

PERCY H. GOODWIN, OF SAN DIEGO, CALIFORNIA.

LIFE-SAVING AND SIGNAL ROCKET.

932,270.

Specification of Letters Patent. Patented Aug. 24, 1909.

Application filed November 3, 1908. Serial No. 460,907.

To all whom it may concern:

Be it known that I, PERCY H. GOODWIN, a citizen of the United States, residing at San Diego, in the county of San Diego and 5 State of California, have invented certain new and useful Improvements in Life-Saving and Signal Rockets; and I do hereby declare the following to be a full, clear, and exact description of the invention, such as 10 will enable others skilled in the art to which it appertains to make and use the same.

My invention relates to life saving and signal devices for use especially at life saving stations, but which may also be carried and 15 employed by vessels of all kinds.

It has for its object to provide an economically constructed and operated device which is an improvement over the method of carrying a life line by a mortar gun now in 20 use at life saving stations, in that it accomplishes the desired result with far greater safety and accuracy.

My invention is not only designed for delivering a line to ships or vessels in distress, but it may also be used for signaling messages in time of war or peace and either 25 on the high seas or on battlefields.

The invention consists in certain novel features of construction and combinations 30 of devices which are hereinafter described and specified in the claims concluding this specification.

In the accompanying drawings illustrating the preferred embodiment of my invention: Figure 1 is a side view of the rocket. 35 Fig. 2 is a central longitudinal section thereof. Fig. 3 is a perspective view showing the rocket in its support ready for discharge. Fig. 4 is a detailed view of the 40 adjustable rocket trough and Figs. 5 and 6 are sectional views taken at right angles to each other through the head of the stand for the rocket trough, and showing more in detail the means of adjusting the same.

Referring more particularly to Figs. 1 and 45 2 of the drawing, A designates the shell of the rocket which is pointed at one end and is provided with a projecting propeller carrying frame K at the other end. A balance 50 plug R is preferably screwed, as at H, into the shell near the pointed front end B thereof and serves to equalize or balance the weight of the line and attachment M therefor at the rear end. Within the main body of 55 the shell there are arranged two truncated-cone-shaped receptacles C and D preferably

made of sheet metal. Said receptacles are tapered toward the rear or propeller carrying end of the rocket. The forward one C is perforated, as at T, and holes U are also 60 formed in the larger end of the receptacle D so as to communicate with the space around the outside of the receptacle C. This arrangement of the receptacles C and D and the perforations T and U provide for an equal distribution of the gases formed by the ignition of explosives placed in the receptacle C and a uniform discharge of said gases through the opening D' at the rear end of the receptacle 65 D whereby a substantially uniform and constant pressure will be exerted by the gases upon the propeller J.

A tube E extends through the center of the rocket to near the extremity of the chamber formed in the pointed front end section B. 70 Said tube is preferably secured to the balance plug R as shown at S in Fig. 2 and the rear end of said tube is fastened in any suitable manner to the supporting frame K for the propeller. A fuse L is passed through this 75 tube and projects at both ends thereof. Slots F and G are provided for igniting the explosives. The front section B is designed to contain signal powder which is fired by the 80 front end of the fuse when the rocket is in flight. The plug I in the end of this section is blown out by the discharge of the signal powder, allowing the colored fire to escape 85 into the air. It should be understood that any liquid or other signal preparation may 90 be used instead of powder.

As illustrated in Fig. 2, the propeller has ball-bearings Q interposed between it and the sleeve O and collar P mounted around the tube E. The life line is to be attached 95 to the swiveled eye N on the bracket M. In Fig. 3 said line is designated V and is shown as coiled upon a pyramid g with one end secured to the base thereof, as at h. The use of the pyramid insures the line uncoiling 100 freely and without interruption.

The rocket trough W is pivotally supported between the uprights X on the head of the stand or tripod 10 by the pins p. Lugs e are adapted to engage the rear end of the shell of the rocket and retain it in proper position in the trough. The tripod comprises in addition to the head, the folding legs d, as usual. The head consists of the lower stationary part b and the upper part Y 110 adapted to turn on said lower part about the pin 15 as an axis. Said pin carries a thumb

nut 20 on its lower end for immovably locking the rotatable part to the fixed part when the former has been adjusted to the desired position. Said rotatable part has a passage 5 25 extending horizontally therethrough, in which is arranged an arcuate rack bar Z depending from the trough. Said rack bar controls the vertical angle of the trough and is secured in the desired position by being engaged by teeth on the lower end of a vertically movable latch k operated by a cam i to which is attached a hand lever a . Said latch is guided by a pin m working in a vertical slot l therein, said pin being fixed to the 10 housing n for the latch. This apparatus just described enables the operator to scientifically adjust either the vertical or horizontal angle of the trough without changing the other which may have been already determined. These adjustments can be made 15 very readily in a practical manner and without undue exertion.

I claim:

1. A rocket of the character described comprising a cylindrical shell having a chamber therein adapted to hold an explosive and provided with an opening in its rear end, a propeller supported beyond the rear end of said shell in position to be driven by the gases discharged from the explosive chamber, and means to ignite the explosive in said chamber.

2. A rocket of the character described comprising a cylindrical shell having a truncated-cone - shaped chamber therein adapted to hold an explosive, the walls of said chamber tapering toward the rear end of the shell which is provided with an opening therein, a propeller supported beyond the rear end of said shell in position to be driven by the 40 gases discharged from the explosive chamber, and means to ignite the explosive in said chamber.

3. A rocket of the character described comprising a cylindrical shell having two truncated - cone - shaped chambers therein arranged end to end for holding an explosive, the walls of both of said chambers being tapered toward the rear end of said rocket, the forward chamber having its lateral wall 50 perforated but cut off from direct communication with the rear chamber, said latter chamber having perforations in its larger end communicating with the space around the outside of said forward chamber, said shell 55 being provided with an opening in its rear end, a propeller supported beyond the rear end of said shell in position to be driven by the gases discharged from the explosive chambers, and means to ignite the explosive 60 in said chambers.

4. A rocket of the character described comprising a cylindrical shell having two truncated - cone - shaped chambers therein arranged end to end for holding an explosive, 65 the walls of both of said chambers being

tapered toward the rear end of said rocket, the forward chamber having its lateral wall perforated but cut off from direct communication with the rear chamber, said latter chamber having perforations in its larger end 70 communicating with the space around the outside of said forward chamber, said shell being provided with an opening in its rear end, a propeller supported beyond the rear end of said shell in position to be driven by 75 the gases discharged from the explosive chambers, and a fuse carrying tube extending through said chambers and having slots therein opening into each.

5. A rocket of the character described 80 comprising a cylindrical shell having a chamber therein adapted to hold an explosive and provided with an opening in its rear end, a fuse carrying tube arranged centrally of said chamber and projecting from the rear of said 85 shell, and a propeller mounted around said projecting portion of said tube in position to be driven by the gases discharged from the explosive chamber.

6. A rocket of the character described 90 comprising a cylindrical shell having a chamber at its rear end adapted to hold an explosive and a separate chamber at its front end for holding signal material, a propeller supported beyond the rear end of said shell in 95 position to be driven by the gases discharged from the explosive chamber through an opening in the rear end of said shell, means to ignite the explosive and signal material in said chambers, and a plug in the wall of 100 the front chamber adapted to be blown out when the signal material is ignited.

7. A rocket of the character described comprising a cylindrical shell having a chamber at its rear end adapted to hold an explosive and a separate chamber at its front end for holding signal material, a propeller supported beyond the rear end of said shell in 105 position to be driven by the gases discharged from the explosive chamber through an opening in the rear end of said shell, a fuse-carrying tube extending through the rear chamber and opening into said chamber and into the front chamber, and a plug in the wall of 110 said front chamber adapted to be blown out when the signal material is ignited.

8. A rocket of the character described comprising a cylindrical shell having a chamber at its rear end adapted to hold an explosive and a separate chamber at its front end for holding signal material, a propeller supported beyond the rear end of said shell in 115 position to be driven by the gases discharged from the explosive chamber through an opening in the rear end of said shell, a fuse-carrying tube extending through the rear chamber and opening near the rear end of 120 said chamber and near the front end of the front chamber, and a plug in the front end wall of 125 said latter chamber adapted to be 130

blown out when the signal material is ignited.

9. A rocket of the character described comprising a cylindrical shell having a chamber therein adapted to hold an explosive and provided with an opening in its rear end, a propeller supported beyond the rear end of said shell in position to be driven by the gases discharged from the explosive chamber, means to ignite the explosive in said chamber, and a balance plug near the forward end of the shell.

10. A rocket of the character described comprising a cylindrical shell having a chamber at its rear end adapted to hold an explosive and a separate chamber at its front end for holding signal material, a balance plug near the front end of said shell and constituting the partition between said chambers, a propeller supported at the rear end of said shell in position to be driven by the gases discharged from the explosive chamber through an opening in the rear end of the shell, means to ignite the explosive and signal material in said chambers, and a plug in the wall of the front chamber adapted to be blown out when the signal material is ignited.

11. The combination, with a stand, of a horizontal turn table mounted on said stand, a combined pivot and clamping bolt passed

vertically through said turn table and stand, a rocket trough carried by said turn table and adapted to swing in a vertical plane, and means to lock said trough at the desired incline.

35

12. The combination, with a stand, of a turn table mounted on said stand, means to lock said turn table when desired, a rocket trough mounted on said turn table and adapted to swing in a vertical plane, an arcuate bar depending from said trough, a latch adapted to clamp upon said bar, a cam fitted in said latch, and a crank connected to said cam for actuating said latch, whereby said trough may be adjusted and retained at the desired incline.

40

13. The combination, with a stand and a rocket trough mounted thereon and having two spaced apart lugs adapted to support a rocket in position to be discharged, of a rocket provided with a propeller-carrying frame having a plurality of wings, the edge of one of which is adapted to rest between said lugs when the rocket is in the trough.

45

In testimony whereof, I affix my signature, in presence of two witnesses.

PERCY H. GOODWIN.
